UNITED STATES PATENT OFFICE.

JAN SONNEVELD, OF SCHELA GURA OCNITSEI, NEAR TARGOVISTE, ROUMANIA.

APPARATUS FOR EXTRACTING LIQUIDS OR GASES.

1,351,139.

Specification of Letters Patent. Patented Aug. 31, 1920.

Application filed March 10, 1917. Serial No. 154,004.

To all whom it may concern:

Be it known that I, JAN SONNEVELD, subject of the Queen of the Netherlands, residing at Schela Gura Ocnitsei, near Targoviste, Roumania, have invented certain new and useful Improvements in Apparatus for Extracting Liquids or Gases, of which the following is a specification.

This invention relates to a new apparatus 10 for drawing off liquids or gases or both liquids and gases, under pressure, and containing mineral substances in granular condition from a container or the like and it relates in particular to apparatus for the extraction of petroleum or other hydrocarbons containing sand or the like from a well.

The known manner of securing under such circumstances a regular ejection of the fluids is by means of valves, with which the passage of the fluid may be throttled. Such valves however, when throttling the passage of fluid, prevent same from passing in a straight line through the valve, part of the valve member proper then projecting into 20 the path of the fluid. Consequently such valves in a short time are fully ground out by the solid substances contained in the fluid and in case the ejection takes place under high pressure the valves are even 25 totally destroyed in a few hours.

According to the present invention the discharge of the fluid (liquids or gases under pressure and containing mineral substances in granular condition) from the well, which 30 is closed for the rest, is conducted through one or more annular or pierced members which are connected either directly or indirectly to the well, said member or members providing a passage for the fluids smaller 35 than the bore of the rest of the conduit, the inner walls of said member or members being substantially parallel to the path of the solid parts contained in the fluid to be discharged.

The said annular or pierced member or members are preferably of cylindrical shape with a central bore. They may consist of a metal, an alloy or a mineral of the same or greater hardness than iron, or they may 45 consist of either of these materials in granular condition and bound by a binding agent.

They are either directly or indirectly connected to the well, or to the pipe by which liquids and gases are discharged from the well, or they are mounted on the mouth of 55 said discharge pipe, but always in such a way as to force the fluids to be discharged to pass through it previous to entering a space of lower pressure.

Referring to the drawings, Figure 1 shows 60 one embodiment of my invention; Fig. 2 is a cross section through a form of nozzle preferably employed by me; and Fig. 3 is a cross section through such a nozzle.

In Fig. 1 of the drawing, 1 designates a 65 cylindrical nozzle having a bore of a diameter which is reduced with regard to the bore of the discharge pipe 2, on the mouth of which it is mounted, the discharge pipe 2 being connected to the well 3.

Fig. 2 shows the discharge member or nozzle 1 on a larger scale. The inner wall of the nozzle is curved near its one end, so as to practically prevent it from being hit by the solid substances contained in the 75 liquids or gases, thereby protecting it against being ground out in a very short time.

Fig. 3 is a cross-section of the nozzle.

Preferably the thickness of the wall of 80 the discharge members (e. g. nozzle 1) is about 15 millimeters in the case of iron being employed, and at least 10 millimeters in case a material of greater hardness is used. The length of the discharge member is dependent on the circumstances for which it is used; preferably it will not be less than 100 millimeters, as by a greater length the wear, which cannot be absolutely avoided, is reduced.

By applying the method of extraction according to the present invention, even under difficult circumstances a relatively quiet and regular discharge may be obtained. The quiet ejection reduces the tendency of the 95 lining of the well to warp, and at the same time prevents the oil bed from breaking off.

Claim:

Apparatus for extracting liquids or gases, under pressure and containing granular material, from wells, comprising a discharge pipe connected substantially horizontally to

the casing of the well and provided at its outer end with a tubular nozzle of considerable length, the bore of which has a diameter smaller than that of the bore of the pipe, the nozzle bore being coaxial with the bore of the pipe and being rounded at its inner end to reduce the wear caused by the granular material.

In testimony whereof I have hereunto set my hand in presence of two subscribing witnesses. 10

JAN SONNEVELD.

Witnesses:

THOM A. VERHAVE,
KUUN WYNBRANT.
